UNITED STATES PATENT OFFICE.

WILLIAM GENTRY SHELTON, OF NEW YORK, N. Y.

AUTOMATIC STOP FOR TALKING-MACHINES.

1,392,081.

Specification of Letters Patent. Patented Sept. 27, 1921.

Application filed March 4, 1920. Serial No. 363,209.

To all whom it may concern:

Be it known that I, WILLIAM GENTRY SHELTON, a citizen of the United States of America, residing in the borough of Manhattan, city, county, and State of New York, have invented certain new and useful Improvements in Automatic Stops for Talking-Machines, of which the following is a specification.

10 This invention relates to improvements in automatic stops for talking machines, and aims to provide improvements therein.

The present invention provides a stop or braking device for talking machines, which 15 automatically operates to stop the operation of the talking machine when the reproducer ceases being fed by the groove in the sound record, as for example, when the reproducer reaches the end of the record. The invention further provides a device, the action of 20 which is automatic, notwithstanding the particular relation which the beginning part, or ending part of the record groove bears to the edges of the record.

25 The invention further provides a device which may require no direct manual operation or setting, the setting being a concomitant of the operation of one of the usual parts of the talking machine, as for example, 30 the reproducer support or carriage.

The invention further provides a device of the character described which may also be manually operated to apply the brake or operate other stopping means, whereby, for 35 example, the record carrier (turntable) may be stopped at any stage of the playing of the record.

40 The invention further provides a transmission by means of which movement may be transmitted from a part on a record carrier of the disk or turntable type and which admits of ready removal of the turntable.

45 The invention further provides a device or devices of the character described, which is simple and durable, which may be cheaply manufactured, readily applied to existing types of talking machines, and which is effective in carrying out its purposes.

50 The invention further provides novel combinations, sub-combinations and arrangements of parts, hereinafter more fully set forth and defined in the annexed claims.

An embodiment of the invention is illustrated in the accompanying drawings. Said 55 embodiment is shown as applied to a talking

machine having a record carrier of the disk or turntable type, and as having a reproducer support or carriage in the form of a "tone arm," or swiveled sound conveying tube.

60 In said drawings,

Figure 1 is a plan view of the invention, applied to a talking machine, the brake being shown in "off" position, and the turntable or record-carrier free to turn.

65 Fig. 2 is a vertical sectional view on the line II-II, Fig. 1.

Fig. 3 is a vertical sectional view on the line III-III, Fig. 1.

70 Fig. 4 is a view similar to Fig. 1, showing the parts in position following the release of the brake from the detent.

75 Fig. 5 is a view similar to Figs. 1 and 4, showing the parts in the position which they occupy at or during the initial playing of the record.

80 Referring to said drawings, A designates the record carrier, which may be of any suitable type, here shown as a disk or turntable, and rotated in any suitable manner. B indicates the reproducer carrier, which may be of any suitable type, and here shown as a swiveled sound conveying tube or "tone arm."

85 Numeral 10 designates a stopping device, such as a brake, which may be of any suitable type, and adapted to operate upon any part of the talking machine which will effect the stopping of the operation thereof, and in particular, stop the operation of the record-carrier. As here shown, the brake 10 comprises a lever pivoted adjacent the rim of the record carrier A, as indicated at 11, and carrying a shoe or pad 13, adapted to make braking contact with the rim of the record carrier. The brake or lever 10 preferably has an extended arm 15, by means of 90 which it may be moved out of contact with the record-carrier.

95 The brake is conveniently spring-pressed, as by means of a spring 17, which normally tends to pull or move the brake into braking contact with the record carrier, and, in this case, a detent 20 is conveniently provided for normally holding the brake out of contact with the record carrier. The detent 20 is conveniently in the form of a bell crank, and having a tooth 21 for engaging the notch in the brake lever 10, and, when so engaged, holding the brake out of braking 100 105 110

position. A spring 23 normally presses the 5 detent against the brake lever 10. The detent is preferably provided with an arm 25, projecting to an accessible place, which permits the detent being moved to release the brake, when the detent is covered by part of the talking machine, as is usually the case.

In the case of talking machines having an 10 electric drive, the part 30 may operate to start and stop the said motor, as by operating a switch in the circuit leading to the motor.

Numeral 30 designates a part adapted to 15 actuate the stopping device or brake, and, in the construction illustrated, to press or strike the detent and thereby release the brake from the detent.

Means are provided for automatically 20 moving the striker or actuating part 30 against the detent 20 or other part of a stopping device (to release the brake from the detent) when the reproducer is no longer advanced in the spiral grooves of the sound 25 record, as for example, when the reproducer reaches the end of the spiral groove. These means comprise a rotary shaft 40, or other suitable means, with which said striker or actuating part 30 is adapted to engage, and, 30 when so engaged, be moved to an indeterminate extent. The rotary shaft 40 for example, may be provided with screw-threads 41, of an indeterminate length, and the striker may be provided with a tooth, clutch- 35 part or the like 42, adapted to engage within the groove between the screw-threads 41.

Means such as a spring 45, attached to 40 an arm 46, attached to the striker or actuating part 30, normally tends to move the striker out of engagement with the screw-threaded shaft 40.

Means are provided for holding the 45 striker or actuating part 30 in engagement with the threads on the screw-threaded shaft 40, against the action of the spring 45, these holding means being conveniently a pin 50, moving with the reproducer. To this end, the pin 50 may be mounted upon the sound 50 conveying tube or "tone arm" B carrying the reproducer, as shown in Figs. 1 and 2.

The action of the holder, which moves for 55 as long a time as the reproducer is moved by the spiral groove of the sound record, is to press the striker or actuating part 30 into engagement with the threaded shaft 40, and hold the said striker or actuating part in such engagement throughout the movement of the pin 50. The threads 41, being of an indeterminate length, continue to move the striker after the pin 50 stops its movement. The striker or actuating part 60 65 30, being thereupon moved away from the holder, is free to move out of engagement with the threaded shaft 40, under the action of the spring 45, thereby bringing the

striker against the detent 20, causing the detent to release the brake, and the brake to stop the machine.

The striker or actuating part 30 is most conveniently in the form of a slide, having 70 a movement parallel to the shaft 40, and also toward and from the coacting part of the stopping mechanism. For guiding the part 30, a lug 60 may be formed thereon, in which lug there is formed a hole which 75 fits somewhat loosely around the shaft 40. There may also be provided a lug 61, struck-up from a plate 63, having an elongated slot 62 therein, permitting a limited oscillation 80 of the striker or actuating part 30 around the lug 60.

The striker 30 may be provided with a reduced or recessed portion 64, whereby in 85 its initial position, it may occupy a position out of engagement with the threaded shaft 40 without striking against or pressing upon the detent 40, and hence causing the detent to release the brake.

After having been moved by the shaft 40, and after having been moved out of engagement therewith, the striker or actuating part is preferably returned to the initial position. This may be effected by any suitable means, but is conveniently effected by attaching the spring 45 at a point 66 in 95 such manner that it has a compound action upon the striker 30, one component of its force being in the direction to move the striker away from the shaft 40, the other component being to move the striker parallel with the shaft 40.

The pin 50 may have a motion derived 105 from or corresponding to the reproducer carrier or support. One method by which the pin 50 is made to maintain its bearing or contact upon the striker or actuating part 30, during or throughout the movement of the reproducer carrier is shown in the accompanying drawing. This means conveniently comprises a compensating device, 110 as cam 70, the face of which is given a contour which compensates for the difference in lineal movement in a common direction, between the said pin 50 and the striker 30.

The shaft 40 may be rotated in any suitable manner. Conveniently the shaft may be provided with a pinion 80, and this may be driven by a worm 81. In the disk or turntable type of talking machine, this worm 81 is conveniently mounted upon the 120 underside of the turntable, and the construction is such that the turntable may be removed or replaced without hindrance, inasmuch as the threads of the worm and the teeth of the pinion 80 readily roll into and 125 out of mesh.

Operation.—The brake or other stopping device being set, or positioned so as to hold the machine from operating, and a record being upon the record-carrier, the turn-table 130

may be released, either by a manual operation of the brake or stopping device by means of the arm 15, for example, or an automatic operation of said means to release the turntable 5 may be effected through the pin 50, by moving the reproducer carrier in an appropriate direction. The reproducer may thereupon be lowered to bring the stylus into contact with the record and the playing of the 10 record commences. At the initial part of the playing, the pin 50 may come in contact with the striker or actuating part 30, or this contact may be established at a somewhat later period, it only being necessary 15 that the pin come in contact with the striker or actuating part some time prior to the reproducer reaching the end of the record. When the pin comes in contact with the part 20 30, the tooth or clutch-part 42 on the striker is brought into engagement with the screw-threads 41 of indeterminate length on the rotating shaft 40. This causes the striker or part 30 to move parallel to the shaft 40, the pin 50 holding the striker engaged with 25 the said shaft 40 until the reproducer reaches the end of the record and the reproducer carrier ceases to move, whereupon the shaft 40 proceeds to move the striker away from the holding pin 50. When released 30 from the holding pin, the striker is free to move out of engagement with the shaft 40 (under the influence of the spring 45, or other force), and against the detent 20, or other coacting part of a stopping device. When the striker or part 30 strikes the detent 20 it turns it on its pivot, so as to release the brake 10. The brake thereupon acts to stop the operation of the machine, as by its shoe coming into contact with the rim of 35 the turntable. When the reproducer carrier is moved to initial position, the striker, being out of engagement with the threads 41, is moved by the spring 45 to initial position. In this position the parts of the brake may 40 be reset to allow the machine to run (either by hand, or by an extra movement of the reproducer carrier) this being permitted by the reduced or recessed portion 64 of the striker. 45 If it is desired to stop the operation of the machine prior to the time that the reproducer reaches the end of the record, this 50 may be readily effected by manipulating the arm 25 of the detent to release the brake from the detent.

The holding pin 50 may be brought into contact with the striker 30 at any period during the playing of the record, so that practically any size record may be used upon 55 the machine, and the particular location of the end part of the groove is of no consequence, as regards the operation of the mechanism to automatically operate the brake or stopping device to stop the operation of the machine.

The inventive ideas herein set forth may receive other mechanical expressions and embodiments than those herein specifically illustrated and described.

What I claim is:—

1. A stopping mechanism for talking machines, comprising a stopping device, and means for actuating said stopping device to stop the operation thereof, said means comprising an actuating part, means for moving 70 said actuating part for an indeterminate period, means moved by the reproducer-support for holding said actuating part in engagement with said indeterminate moving means, and means normally tending to move 75 said actuating part out of engagement with said indeterminate moving means, said indeterminate moving means being adapted to move said actuating part away from said holding means and allow said actuating part 80 to move to actuate said stopping device, when said holding means ceases to move by reason of the reproducer ceasing to be moved by the record.

2. A device according to claim 1, further 90 comprising means between said actuating device and said holding means for compensating for the difference in the motion imparted to said actuating device by said indeterminate moving means and the motion 95 of said holding means when in motion.

3. A device according to claim 1, further comprising a cam on said actuating part on which said holding means is adapted to press when in motion, said cam being adapted 100 to compensate for difference in the motion imparted to said actuating device by said indeterminate moving means and the motion of said holding means toward said cam.

4. A device according to claim 1, in which said indeterminate moving means comprise a continuously rotating screw-threaded shaft.

5. A device according to claim 1, in which 110 said indeterminate moving means comprises a continuously rotating screw-threaded shaft, and in which said actuating device comprises a slide having a sliding movement parallel with said shaft, and movement to 115 and from said shaft, under the co-action of said holding part.

6. A device according to claim 1 in which said holding means comprise an attachment adapted to be mounted on the tone-arm 120 of a talking machine.

7. A device according to claim 1, further comprising means adapted to be actuated by said holding means to move said stopping device from stopping position to a non-stopping position.

8. A device according to claim 1, further comprising manually operable means for moving said stopping device to non-stop- 125 ping position.

9. A device according to claim 1, in which said indeterminate moving means comprises a continuously rotating screw-threaded shaft, a spur gear thereon and a worm, said 5 worm being attachable to a rotary turntable, and said worm and gear being adapted to roll into and out of mesh, whereby said turntable may be readily removed.

10. A device according to claim 1, in 10 which said means which normally tends to move said actuating part out of engagement with said indeterminate moving means, acts to return said actuating part to an initial position when disengaged.

11. A device, according to claim 1, in 15 which said stopping device comprises a brake and a detent, said actuating part co-acting with said detent.

12. In combination, a stopping device, an 20 actuating part therefor, a driving part to which said actuating part is adapted to be connected and disconnected, said actuating part being adapted to be moved by said driving part when connected thereto, and, 25 in disconnected position, to coact with said stopping device, and a part connected with the reproducer carrier for holding said actuating part connected to said driving part, said driving part having a speed related to 30 the rate of movement of said reproducer part, said actuating part, when said reproducer carrier ceases to hold said actuating part connected to said driving part, actuating said stopping device.

13. In combination, a stopping device, an 35 actuating part therefor, a driving part, a clutch part between said actuating part and said driving mechanism, adapted to connect and disconnect said actuating part and driving mechanism, said actuating part, in unclutched position coacting with said stopping device, and a part connected with the reproducer carrier for holding said clutch part in connection with said driving means, 40 said driving part having a speed related to the rate of movement of said reproducer 45

part, said actuating part, when said reproducer ceases to hold said clutch part connected to said driving part, actuating said stopping device.

14. In combination, a stopping device, an 50 actuating part therefor, a driving part to which said actuating part is adapted to be connected and disconnected, said actuating part being adapted to be moved by said driving part, when connected thereto, and, in disconnected position, to coact with said stopping device, and a part connected with the reproducer carrier for holding said actuating part connected to said driving part, 55 said driving part having a speed related to the rate of movement of said reproducer part, compensating means for effecting an equal movement of said reproducer part and said driving part on said actuating 60 part, said actuating part, when said reproducer carrier ceases to hold said actuating part connected to said driving part, actuating said stopping device.

15. In combination, a stopping device, an 65 actuating part therefor, a driving part to which said actuating part is adapted to be connected and disconnected, said actuating part being adapted to be moved by said driving part when connected thereto, and, in 70 disconnected position, to coact with said stopping device, said driving part having a speed related to the rate of movement of said reproducer part, and a part connected with the reproducer carrier for holding said 75 actuating part connected to said driving part, said actuating part, when said reproducer carrier ceases to hold said actuating part connected to said driving part, actuating said stopping device.

In witness whereof I have hereunto signed my name.

WILLIAM GENTRY SHELTON.
